(57) **CLAIM**

I claim the ornamental design for portion of a computer screen with a color palette icon, as shown and described.

DESCRIPTION

The file of this patent contains at least one drawing or photograph executed in color. Copies of this patent with color drawing(s) or photograph(s) will be provided by the Patent and Trademark Office upon request and payment of necessary fee.

The single view is a front view of a portion of a computer screen with color palette icon, the broken line drawing of an undefined portion of a computer screen is for illustrative purposes only and forms no part of the claimed design.

The white background in the drawing is disclaimed.
